(57) **CLAIM**

The ornamental design for a television receiver, as shown and described.

DESCRIPTION

FIG. 1 is a rear perspective view of a television receiver showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image;

FIG. 6 is a reference front perspective view thereof showing the claimed part of the television receiver by hatching;

FIG. 7 is a reference rear view thereof showing the claimed part of the television receiver by hatching;

FIG. 8 is a cross-sectional view taken along line A-A'; and, FIG. 9 is a cross-sectional view taken along line B-B'.

The broken lines are for illustrative purposes only and form no part of the claimed design.

1 Claim, 9 Drawing Sheets
